SUPPORTING PIN

Hampton Jennings Dailey, Bloomfield, and William John Knochel, Irvington, N. J., assignors to Westinghouse Electric & Manufacturing Company, East Pittsburgh, Pa., a corporation of Pennsylvania

Application December 30, 1941, Serial No. 424,862

9 Claims. (Cl. 250—27.5)

This invention relates to supporting pins, and more particularly to pins employed as part of electron discharge devices for support of interior parts from the glass or other ceramic wall of the envelope.

In the electronic art, the production of heat in use of the device as well as the employment of heat, as for soldering, sealing, flashing, and other purposes, results in different parts, especially those having different coefficients of expansion, being subjected to strains. Many defective devices are directly traceable to the deleterious heat effects.

An object of the present invention is to overcome deleterious effects of heat used upon or developed by an electron discharge device.

Another object of the invention is to provide for accommodation of uneven or dissimilar expansion of normally rigid and connected parts.

A further object of the invention is to enable metallic parts in an electron discharge device to expand without undue hinderance from connection with the glass envelope, and vice versa.

Yet another object of the invention is to reduce transmission of heat due to conduction to or from the interior electrodes and closely associated parts.

Still further objects will appear as the description progresses, both by direct recitation thereof and by implication from the context.

Referring to the accompanying drawing in which like numerals of reference indicate similar parts throughout the several views;

Figure 1 is a sectional view of an electron discharge device showing our invention incorporated therein;

Figure 2 is a detail cross-section on line II—II of Fig. 1; and

Figure 3 is a perspective view of one of the pins or posts embodying our invention.

In the specific embodiment of the invention illustrated in said drawing, there is shown, by way of example, an electron discharge device which comprises a glass or other ceramic bowl 10, here represented as part of an evacuated envelope, a metallic dome-like anode 11 being sealed in the rim thereof to constitute the complementary part of said envelope. For convenience of reference, said glass bowl 10 will be considered as the base portion of the envelope. From the bottom of this bowl or base protrude a plurality of thimbles 12 of similar character and constituting prongs as a means for making exterior circuit connections and for support of the device. These thimbles have enlarged cylindrical feather

edges 13 next the glass bowl and are sealed thereby to the glass. A feature of the present invention is to overcome prevalent disruption of this sealed connection and/or breakage or cracking of the glass in the vicinity thereof.

The electron discharge device includes therein a grid 14 and cathode 15. Supporting connection from the mentioned electrodes to the said thimbles is made by pins or posts of which those shown are designated 16, 17, 18 and 19 for reference purposes. The pins or posts are essentially the same, differing only in detail, so that description of one will answer for all. For that purpose, particular attention will be directed to the pin or post 16 at the left of Fig. 1, section thereof in Fig. 2, and perspective view thereof comprising Fig. 3.

Said pin or post is a relatively long thin cylindrical structure the lower end of which is semi-spherical, as at 20. The upper end of the particular pin shown has a coaxial threaded hole 21 therein. Intermediate the ends of the pin, the same provides a thin shank 22 coaxial with the larger-diameter lower and upper end portions 23, 24 respectively. The intermediate portion or shank 22 is less than half the length of the entire pin and preferably not more than a third of the length nor any longer than either of the end portions 23, 24. Furthermore, the diameter of the shank is preferably not more than half the diameter of the upper end portion. Diameter of the lower end portion 23 is variable to fit the thimble in which it is mounted.

By the construction shown and described utilizing dimensions of the approximate proportions given, and appropriate choice of flexible material, preferably hard copper, adequate supporting strength is maintained. The end portions 23, 24 of the pin are rigid, but by virtue of the reduced diameter of the shank, a degree of lateral flexing of the pin thereat is available. Resistance or counter-force to such flexing is obtained by the mounting of the lower part of the pin in the thimble and mounting of the feather-edge of the thimble in the glass of the bowl. That mounting is adequate to retain the lower end portion 23 of the pin fixed while the shank portion flexes, without disrupting the seal or cracking the glass.

It is appropriate to note that a plate 25 carrying grid 14 is situated transversely at the top of the post 15 described and secured thereto by screw 26, and is attached to other posts shown and not shown. That plate, under varying heat conditions expands and contracts, the pins being necessarily shifted thereby laterally at their up-

per ends. Prior to our invention that shifting resulted in a necessary shift or swing of the entire pin or post, with terrific strain on the feather-edge of the thimble to compensate therefor. By virtue of the present invention, the thinned section of the pin or post introduces flexibility therat which thereby absorbs most of the strain heretofore carried by the feather-edge. In actual practice, failures and breakage due to strains on the thimble and associated glass have been practically eliminated.

It is also of importance to observe that while the particular pin selected for descriptive purposes above is one connected to the grid-supporting plate, other similar pins support the cathode through appropriate connections and plates. The lower ends of the pins substantially fit within the prong portions of thimbles 12 and are soldered or otherwise held therein. By virtue of the thinned portion or shank 22 of the pin, the heat absorbed by the pin during soldering in the thimble is materially reduced due to the reduced cross-section and consequent lessened conduction so that a faster soldering is obtained. Again, the reduced cross-section and lessened conduction of heat by the pin shank, decreases heat conveyed to the lower end portion 23 of said pin and its encompassing thimble which is a greatly desired circumstance.

Since the various details of construction, as well as the precise relation and functioning of parts are subject to variation and change without departing from the inventive concept or scope of the invention, it is intended that all matter contained in the specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

We claim:

1. In an electronic device having an electrode, a supporting pin for said electrode, said pin having rigid portions and having a flexible portion, all of said portions being self-sustaining and capable of sustaining other portions, said pin as a whole constituting a support for said electrode.
2. In an electronic device having an electrode, a supporting pin for said electrode, said pin having rigid portions and having a flexible portion between said rigid portions, all of said portions being self-sustaining and capable of sustaining other portions, said pin as a whole constituting a support for said electrode.

3. In an electronic device having a transverse plate and an electrode carried by said plate, an envelope having a thimble exterior thereof, and a pin connecting said plate and thimble, said pin having a flexible portion.

4. In an electronic device having a transverse plate and an electrode carried by said plate, an envelope having a thimble exterior thereof, and a pin connecting said plate and thimble, said pin having a portion of its length thinned to less diameter than other portions thereof.

5. In an electronic device having a transverse plate and an electrode carried by said plate, an envelope having a thimble exterior thereof, and a pin connecting said plate and thimble, said pin having a portion of its length thinned to less diameter than other portions thereof, said thinned portion being flexible.

6. In an electronic device having a transverse plate and an electrode carried by said plate, an envelope having a thimble exterior thereof, and a pin connecting said plate and thimble, said pin having a portion of its length thinned to less diameter than other portions thereof, said thinned portion being flexible and the remaining portions of the pin being rigid.

7. In an electronic device, a supporting pin of elongated cylindrical construction providing end portions and an intermediate self-sustaining flexible shank portion the diameter whereof is materially less than the diameter of at least one end portion thereby permitting lateral displacement of one end portion with respect to the other by flexing of the intermediate shank portion.

8. In an electronic device, a supporting pin of elongated cylindrical construction providing end portions and an intermediate self-sustaining flexible shank portion the length and diameter whereof is less than the length of either of said end portions.

9. In an electronic device having a transverse plate and an electrode attached to said plate, a glass envelope having a metallic thimble exterior thereof with an enlarged marginal end secured to the glass of said envelope, a pin in part within said thimble and passing through the enlarged end thereof into the envelope and secured therein to said plate, said pin having a thinned portion at the part thereof passing through the said enlarged marginal end of the thimble, said thinned portion being flexible and thereby obtaining flexure as required in the vicinity of the junction between the glass envelope and the metallic thimble.
